(57) **ABSTRACT**

A gaming machine is described herein. The gaming machine includes a processor programmed to execute an algorithm including the steps of displaying a game screen including a plurality reels, a bonus wheel including a plurality of wheel wedges displaying prize symbols and a prize selector, and a bonus wheel meter including a number of bonus wheel symbols. The processor is programmed to spin and stop the reels to display an instance of the game, detect an appearance of a bonus wheel symbol appearing in the reels with the reels stopped, and increase the number of bonus wheel symbols included in the bonus wheel meter based on the detected bonus wheel symbol. The processor initiates a bonus wheel feature including a spin of the bonus wheel upon determining the increased number of bonus wheel symbols included in the bonus wheel meter is equal to a predefined number of bonus wheel symbols.

GAMING MACHINE AND METHODS OF OPERATING GAMING MACHINES**CROSS REFERENCE TO RELATED APPLICATION**

This application claims priority to U.S. Provisional Patent Application Ser. No. 63/143,299, filed Jan. 29, 2021, the disclosure of which is hereby incorporated by reference in its entirety.

TECHNICAL FIELD

The present invention relates to gaming machines and control methods for operating gaming machines.

BACKGROUND ART

A gaming machine represented by a slot machine is highly popular among casino customers as a device that provides gaming that is easy to enjoy, and recent statistics report that sales from gaming machines account for the majority of casino earnings. Initial slot machines were simple devices, wherein an inserted coin is received, a configured reel rotates and stops mechanically according to a handle operation, and a win or a loss is determined by a combination of symbols stopped on a single pay line. However, recent gaming machines, such as mechanical slot machines driven by a highly accurate physical reel via a computer controlled stepping motor, video slot machines that display a virtual reel on a display connected to a computer, and various gaming machines that apply similar technology to other casino games are quickly advancing. For the manufacturers that develop these gaming machines, an important theme is to provide an attractive game that strongly attracts casino customers as players and improves the functionality of the gaming machine.

The present invention solves one or more of the problems identified above.

SUMMARY OF THE INVENTION

In one aspect of the present invention, a gaming machine is provided. The gaming machine includes a cabinet, a display device mounted to the cabinet, and a control unit operably coupled to the display device. The control unit includes a processor programmed to execute an algorithm including the steps of displaying a game screen on the display device including a plurality of reels displaying a plurality of game symbols, a bonus wheel positioned above the plurality of reels and including a plurality of wheel wedges displaying prize symbols and a prize selector, and a bonus wheel meter including a number of bonus wheel symbols. The processor is programmed to spin and stop the reels to display an instance of the game, detect an appearance of a bonus wheel symbol appearing in the reels with the reels stopped, and increase the number of bonus wheel symbols included in the bonus wheel meter based on the detected bonus wheel symbol. The processor also initiates a bonus wheel feature including a spin of the bonus wheel upon determining the increased number of bonus wheel symbols included in the bonus wheel meter is equal to a predefined number of bonus wheel symbols.

In another aspect of the present invention, a method of operating a gaming machine is provided. The gaming machine includes a cabinet, a display device mounted to the cabinet, and a processor operably coupled to the display

2

device. The method includes the processor performing an algorithm including the steps of displaying a game screen on the display device including a plurality of reels displaying a plurality of game symbols, a bonus wheel positioned above the plurality of reels and including a plurality of wheel wedges displaying prize symbols and a prize selector, and a bonus wheel meter including a number of bonus wheel symbols. The processor is programmed to spin and stop the reels to display an instance of the game, detect an appearance of a bonus wheel symbol appearing in the reels with the reels stopped, and increase the number of bonus wheel symbols included in the bonus wheel meter based on the detected bonus wheel symbol. The processor also initiates a bonus wheel feature including a spin of the bonus wheel upon determining the increased number of bonus wheel symbols included in the bonus wheel meter is equal to a predefined number of bonus wheel symbols.

In another aspect of the present invention, a non-transitory computer-readable storage media having computer-executable instructions embodied thereon to operate a gaming machine is provided. The gaming machine includes a cabinet, a display device mounted to the cabinet, and a processor operably coupled to the display device. When executed by the processor the computer-executable instructions cause the processor to perform an algorithm including the steps of displaying a game screen on the display device including a plurality of reels displaying a plurality of game symbols, a bonus wheel positioned above the plurality of reels and including a plurality of wheel wedges displaying prize symbols and a prize selector, and a bonus wheel meter including a number of bonus wheel symbols. The processor is programmed to spin and stop the reels to display an instance of the game, detect an appearance of a bonus wheel symbol appearing in the reels with the reels stopped, and increase the number of bonus wheel symbols included in the bonus wheel meter based on the detected bonus wheel symbol. The processor also initiates a bonus wheel feature including a spin of the bonus wheel upon determining the increased number of bonus wheel symbols included in the bonus wheel meter is equal to a predefined number of bonus wheel symbols.

BRIEF DESCRIPTION OF DRAWINGS

45 Non-limiting and non-exhaustive embodiments of the present invention are described with reference to the following figures. Other advantages of the present disclosure will be readily appreciated, as the same becomes better understood by reference to the following detailed description when considered in connection with the accompanying drawings wherein:

FIG. 1A is a perspective view of a gaming machine, according to an embodiment of the present invention;

FIGS. 1B-1G are perspective views of the gaming machine, according to other embodiments of the present invention;

FIG. 2 is a functional block diagram of the gaming machine in FIGS. 1A-1D;

FIG. 3 is an illustration of a game displayed on a display area of the gaming machine, according to an embodiment of the present invention;

FIG. 4 is an illustration of virtual reels that may be used with the game shown in FIG. 3, according to an embodiment of the present invention;

FIGS. 5-8 are block diagrams of a game control unit that may be used with to perform the function of executing a game on the gaming machine;

FIG. 9 is a functional block diagram of a server computer system, according to an embodiment of the present invention;

FIG. 10 is a front view of a mobile computing device that may be used with the server computer system of FIG. 9;

FIG. 11 is an illustration of exemplary reel strip data file for use in generating virtual reels shown in FIG. 4 with symbol arrangements showing the order of symbols displayed on the display area of the game, according to an embodiment of the present invention;

FIG. 12 is an illustration of a reel stop position data file that may be used to execute the game, according to an embodiment of the present invention;

FIG. 13 is an illustration showing one example of a pay line set on the determination area of the game;

FIG. 14 is a flow chart illustrating an algorithm used during operation of the gaming machine and/or the mobile computing device to execute the game, according to one embodiment of the present invention;

FIG. 15 is a flow chart illustrating another algorithm used during operation of the gaming machine and/or the mobile computing device to execute the game, according to one embodiment of the present invention;

FIGS. 16-17 are illustrations of data files that may be used to execute the algorithm shown in FIG. 15; and

FIGS. 18-22 are exemplary illustrations of game screens illustrating the algorithm shown in FIG. 15.

Corresponding reference characters indicate corresponding parts throughout the drawings.

DETAILED DESCRIPTION OF EMBODIMENTS

With reference to the drawings and in operation, the present invention is directed towards a gaming machine, a control method for a gaming machine, and a program for a gaming machine and/or mobile computing device that provides a game to a player. The gaming machine according to the present embodiment, receives a predetermined game value from the player, generates a game result, and provides a payout to the player according to the game result and one or more pay tables. The gaming machine includes a gaming cabinet that includes a display device and a user input device. The display device includes a display configured to display computer generated graphics. The user input device includes a plurality of input buttons that allows a player to initiate game play and interact with video images being displayed on the display device. The gaming machine includes a control unit having a computer processor that is programmed to generate and display a structured graphic user interface displayed on the display device using computer generated graphics. The structured graphic user interface includes a plurality of virtual reels displaying game symbols within a grid. The control unit is also programmed to animate the virtual reels to simulate spinning the virtual through the grid and stop the virtual reels to reveal an outcome of a game. The control unit is also programmed to generate and present additional computer animations in specific animated sequences to display bonus features associated with the game.

Referring to FIGS. 1A-1D, in the illustrated embodiment, the gaming machine 10 includes a cabinet 12 providing a display unit 14 and a control panel 16 and may also house a player tracking or ranking unit 18. The cabinet 12 also houses a game control unit 20 (see FIG. 2) that controls each part (see below). The control unit 20 also implements a random number generator (RNG) that is used during operation of the game. Each configuration is described below.

The display unit 14 may be liquid crystal display devices and/or organic EL display devices and the like, and by controlling via each control unit 20, the display area mentioned below functions as a display unit 14 provided to the player. In some embodiments, the display unit 14 may include an upper display 22 and a lower display 24. As shown FIGS. 1A, 1F, and 1G, in some embodiments, the upper and lower displays 22, 24 are shown on a single display device. In other embodiments, as shown in FIGS. 1B-1E, the upper and lower displays 22, 24 may be shown on multiple display devices.

Speakers 26 are provided on the left and right of the cabinet 12, and by controlling via the control unit 20, sound is provided to the player. On the control panel 16, a bill/ticket identification device 28, a printer device 30, and an operation unit 32 are provided.

The player tracking unit 18 may be housed on the center of the front surface of the cabinet 12 below the display unit 14. The player tracking unit 18 has a card reader that 20 recognizes a player identification card, a display that presents data to the player, and a keypad that receives input by the player. This type of player tracking unit 18 reads information recorded on the player identification card inserted by the player into the card reader and displays the 25 information and/or information acquired by communicating with the external system on the display, by cooperatively operating with the control unit 20 mentioned below or an external system. Further, input from the player is received by the keypad, the display is changed according to the input, and communication with the external system is carried out 30 as necessary.

The bill/ticket identification device 28 is disposed on the control panel 16 in a state where the insertion opening that a bill/ticket is inserted into is exposed, an identification part 35 that identifies a bill/ticket by various sensors on the inside of the insertion opening is provided, and a bill/ticket storage part is provided on the outgoing side of the identification part. The bill/ticket identification device 28, receives and 40 identifies bills/tickets (including vouchers and coupons) that are the game value as a game executing value, and notifies the control unit 20 mentioned below.

The printer device 30 is disposed on the control panel 16 in a state where the ticket output opening that a ticket is output from is exposed, a printing part that prints predetermined information on a printing paper on the inside of the ticket output opening is provided, and a housing part that houses the printing paper inside the paper inlet side of the printing part is provided. The printer device 30, under the control of the control unit 20 mentioned below, prints 45 information on paper and outputs a ticket according to credit payout processing from the gaming machine 10. The output ticket can use the payout credit as game play by being inserted into the bill/ticket identification device 28 of another gaming machine or can be exchanged for cash by a 50 kiosk terminal inside of the casino or a casino cage.

The operation unit 32 receives the operation of the player. The operation unit 32 includes a group of buttons 34 that receives various instructions from the player on the gaming machine 10. The operation unit 32, for example, may 55 include a spin button and a group of setting buttons. The spin button receives an instruction to start (start rotating the reel) an instance of the game. The group of setting buttons 34 includes a group of bet buttons, a denomination button, a group of line-designation buttons, a max bet button, and a payout button and the like. The group of bet buttons receives an instruction operation regarding the bet amount of credits (bet number) from the player. The group of line-designation

buttons receive an instruction operation that designate a pay line subjected to a line judgment below from the player. The max bet button receives an instruction operation regarding the bet of the maximum amount of credits that can be bet at one time from the player. The payout button receives an instruction operation instructing a credit payout accumulated in the gaming machine 10. The gaming machine 10 also includes illumination devices 36 that provides decorative lighting to the gaming machine 10.

In one embodiment, the control panel 16 includes a plurality of user input devices that may include an acceptor device which accepts media associated with a monetary value to establish a credit balance, a validator configured to identify the physical media, a cash-out button actuatable to cause an initiation of a payout associated with the credit balance. The acceptor device may include a touchscreen display associated with the display unit 14 and/or the player tracking unit 18, the bill/ticket identification device 28, the operation unit 32, the player tracking unit 18, a coin slot, a ticket in ticket out (TITO) system, a bill acceptor, and/or any suitable device that enables the gaming machine 10 to receive media associated with a monetary value and establish a credit balance for use in playing the gaming machine 10. In one embodiment, the acceptor device may be configured to receive physical media such as, for example, a coin, a medal, a ticket, a card, a bill, currency, and/or any suitable physical media that enables the gaming machine 10 to function as described herein. The acceptor device may also be configured to accept virtual media such as, for example, a player tracking account, a virtual credit balance, reward points, gaming credits, bonus points, and/or any suitable virtual media that enables the gaming machine 10 to function as described herein.

For example, in one embodiment, the coin slot may include an opening that is configured to receive coins and/or tokens deposited by the player into the gaming machine 10. The control unit 20 converts a value of the coins and/or tokens to a corresponding amount of gaming credits that are used by the player to wager on games played on the gaming machine 10. The bill acceptor may include an input and output device that is configured to accept a bill, a ticket, and/or a cash card into the bill acceptor to enable an amount of gaming credits associated with a monetary value of the bills, ticket, and/or cash card to be credited to the gaming machine 10. In one embodiment, the bill acceptor also includes a printer (not shown) that is configured to dispense a printed voucher ticket that includes information indicative of an amount of credits and/or money paid out to the player by the gaming machine 10 during a gaming session. The voucher ticket may be used at other gaming devices, or redeemed for cash, and/or other items as part of a casino cashless system.

FIG. 2 shows a functional block diagram of the gaming machine 10, according to the present embodiment. The gaming machine 10 provides the control unit 20. Within the cabinet 12, control unit 20 includes a control board equipped with a central processing unit 38 (abbreviated as CPU below) including a processor, an interface unit (or part) 40, a memory device including a memory 42 and a storage 44, and the like are incorporated. The control board is configured so that communication is possible through the interface unit 40 and each of the components equipped on the cabinet 12. The CPU 38 controls the operation of each component by executing the program recorded in the memory 42 or the storage 44 of the CPU 38 and provides a game to the player. The function of the CPU 38 is to execute and display the game on the display unit 14 of the gaming machine 10.

The control unit 20 is configured as the interface unit 40 including a chip set providing communication functions of the CPU 38, a memory bus connected to a CPU 38, various expanding buses, serial interfaces, USB interfaces, Ethernet 5 (registered trademark) interfaces and the like, and a computer unit where the CPU 38 provides the addressable memory 42 and the storage 44 through the interface unit 40. The memory 42 can be configured to include RAM that is a volatile storage medium, ROM that is a nonvolatile storage medium, and EEPROM that is a rewritable nonvolatile storage medium. The storage 44 provides the control unit 20 as an external storage device function, can use reading devices such as a memory card that is a removable storage medium, and a magneto optical disk and the like, and can use hard disks.

On the interface unit 40, in addition to the CPU 38, the memory 42, and the storage 44, a bill/ticket identification unit controller 46, a printer unit controller 48, the player tracking unit 18, a graphic controller 50, an input controller 52, and a sound controller 54 are connected. That is, the control unit 20 is connected to the operation unit 32 through the input controller 52 and connected to the display unit 14 through the graphic controller 50. Further, when illumination devices 36 that provides decorative lighting to the gaming machine 10 is provided, the illumination is controlled under the control of the control unit 20 on the interface unit 40, and an illumination controller 56 that controls the illumination devices 36 to provide a decorative lighting effect may be connected.

The control unit 20, which includes memory 42 and storage 44, controls each part by executing a program stored in the memory 42 and the storage 44, and provides a game to the player. Here, for example, the memory 42 and storage 44 may be configured to store a program and data of an operating system and subsystem that provide the basic functions of the control unit 20 to the EEPROM of the memory 42 and stores a program and data of an application that provides a game to the storage 44. According to such a configuration, it can be easy to change or update a game by replacing the storage 44. Further, the control unit 20 may be a multiprocessor configuration that has a plurality of CPUs.

Each block connected to the control unit 20 is described below. The bill/ticket identification unit controller 46 operates the bill/ticket identification device 28 to receive bills/tickets in the insertion opening and notifies the control unit 20 of identifying information corresponding to the assortment of bills or the payout processing of credits. The bill/ticket identification unit controller 46 notifies the information to the control unit 20, and the control unit 20 increases the usable credit amount inside of the game according to the notified content. The printer unit controller 48 corresponds to the printer device 30, and under the control of the control unit 20 that receives an operation of the payout button of the group of setting buttons 34, information corresponding to the credit payout processing from the gaming machine 10 is printed and output on a printed ticket.

The player ranking (or tracking unit) unit 18 cooperatively operates with the control unit 20 and sends and receives information and the like of the player from the casino management system. The graphic controller 50 controls the display unit 14, under the control of the control unit 20, and displays a display image that includes various graphic data. The sound controller 54 drives the speakers 26 under the control of the control unit 20, and provides various sounds such as an announcement, sound effects, BGM and the like.

Further, the interface unit 40, has various communication interfaces for communicating with the exterior of the gaming machine 10, for example the interface unit 40 can communicate with an external network by Ethernet 58, 60, and a serial interface 62. In the present embodiment, one example shows when there is communication between a well-known server-side gaming network 58 (Server Based Gaming), a G2S network 60 (Game to System), and a slot information system 62 (Slot Data System), respectively.

FIG. 3 schematically shows a display area 64 provided by the gaming machine 10. Such a display area 64 is displayed on the display unit 14 (the upper display 22 and/or the lower display 24) by the control unit 20 executing a predetermined program. In the illustrated embodiment, the display area 64 is displayed on the lower display 24. For instance, as shown, during a game, the upper display 22 may be utilized to display game related information, e.g., game title information and/or graphics.

In one aspect of the present invention, the control unit 20 executes a game execution program to provide a game 66 that includes a primary game 68 and one or more bonus feature events. The control unit 20 displays a game screen within the display area 64 that includes the primary game 68 and the bonus feature events. In the illustrated embodiment, the primary game 68 and the bonus feature events are displayed on the lower display 24. The upper display 22 may be used to display animations and/or game identifying information during the game and/or during an attract mode. Further, the lower display 24 may display a decorative area, and an area that displays credit amount, bet number, and a credit amount obtained by winning (WIN number) and the like. In another embodiment, the primary game 68 may be displayed in the lower display 24 and the bonus feature events may be displayed in the upper display 22.

In the illustrated embodiment, the primary game 68 includes a video slot game using a plurality of virtual reels 70, 72, 74, 76, 78 (shown in FIGS. 3-4). The video slot game utilizes a grid 80 in the display area 64. The illustrated embodiment shows the state of displaying the display area 64 in the lower display 24. By using such a display area, the gaming machine 10 of the present embodiment operates as a slot machine that pays a payout according to a winning combination of symbols displayed on the display area 64.

The display unit 14 displays a plurality of game symbols in the grid 80. The grid 80 has a plurality of rows (r) and columns (c). The grid 80 is configured by a plurality of cells 82 that are the stop position of symbols. On each of the plurality of cells 82 of the display area 64, one symbol is stopped and displayed.

In the illustrated embodiment, the grid 80 is displayed with fifteen cells 82 arranged in three rows and five columns, and the control unit 20 generates five virtual reels 70, 72, 74, 76, 78 for use in displaying the primary game 68. On each cell 82 of the grid 80, as shown in FIG. 3, a game symbol 84 is displayed based on the symbol arrangement of virtual reels including virtual reels 70, 72, 74, 76, 78 (also shown in FIG. 4) configured as a virtual reel set 86. That is, the cells 82 of the grid 80 correspond to the virtual reels 70 to 78, by column, and the game symbols 84 disposed on predetermined parts of each virtual reels 70 to 78 are displayed. In the illustrated embodiment, each of the virtual reels 70 to 78 displays multiple symbols within a corresponding column with the virtual reel in a stopped position. For example, as shown in FIG. 3, when stopped, each virtual reel 70 to 78 displays game symbols within each corresponding column. Furthermore, by moving (scrolling or spinning) each game symbol 84 by column based on the symbol arrangement of

the virtual reels 70 to 78, the game symbols 84 displayed in the cells 82 of the grid 80 change, and by stopping the movement (scrolling or spinning) by columns, the game symbols 84 are stopped. Here, the virtual reels 70 to 78 are data where the control unit 20 uses a program having the memory 42 or the storage 44, and data showing the symbol arrangement (i.e., the order of symbols on each reel strip) regulated by each cell column. Further, the virtual reel set 86 is a general term for such virtual reels 70 to 78.

10 In some embodiments, the control unit 20 generates each virtual reel 70 to 78 using reel strip data files 88 (shown in FIG. 11) and symbol image data files stored in memory 42 and/or storage 44. The reel strip data file 88 includes a reel designation 90 associated with each virtual reel 70 to 78 and 15 sequential symbol position logic cells 92 associated with each reel designation 90. Each symbol position logic cell 92 includes indicators for rendering the virtual reels with a plurality of game symbols. The reel strip data file 88 includes information associated with a plurality of reel strips 94, 96, 98, 100, 102 that correspond to each virtual reel 70 to 78 and are used to generate virtual reel 70 to 78. Each reel strip 94, 96, 98, 100, 102 includes a number of symbol positions 104 configured to be populated by game symbols 84 that are selected from symbol image data files stored in 20 memory 42 and/or storage 44. The reel strips 94-102 also include reel stop positions 106 associated with each symbol position 104. The symbol positions 104 and the corresponding game symbols 84 are arranged in an order defined by each reel strip 94, 96, 98, 100, 102. In addition, one or more reel strips 94, 96, 98, 100, 102 includes a different number of symbol positions 104.

25 In some embodiments, each reel strip 94, 96, 98, 100, 102, includes a plurality of fixed symbol positions 104 for displaying game symbols 84. Each fixed symbol position 30 35 40 45 includes instructions for displaying a predefined game symbol 84 selected from a set of game symbols 84 included in a game symbol image data file. For example, for each play of the game, the fixed symbol positions 104 have an associated predefined game symbol 84 from a symbol set. The game symbol image data file includes the details of game symbols 84 populating the fixed symbol positions 104 and includes varieties of game symbols 84. This symbol set includes card symbols ("9", "10", "J", "Q", "K", and "A") that imitate playing cards as regular symbols, and picture symbols ("PicA", "PicB", "PicC", and "PicD") that show a pattern. Further, this symbol set includes a wild symbol ("Wild") that is substituted as another symbol when a win combination is determined and a special symbol ("Special") that may be used to determine if a game feature is to be provided. Each of these symbols have a different rank from each other regarding their value when winning, their rank gradually raises in this order: "9", "10", "J", "Q", "K", "A", "PicE", "PicD", "PicC", "PicB", "PicA". A combination of symbols that includes high-ranking symbols when winning, 50 55 can obtain a larger winning payout compared to a combination of low-ranking symbols when winning.

One or more of the reel strips 94, 96, 98, 100, 102 may also include a plurality of variable symbol positions 105 that display a varying inner symbol ("inner"). The variable symbol positions 105 are populated using a variable symbol reel strip data file and/or a variable symbol weight table. The variable symbol reel strip data file includes a variable symbol reel strip that includes a number of symbol positions populated by game symbols that are selected from game symbol image files, and stop positions associated with each symbol position. When generating the virtual reels 70 to 78, the control unit 20 is programmed to populate the variable

symbol positions 105 by randomly selecting game symbols from the predefined group of symbols using the variable symbol reel strip. For example, the control unit 20 may be programmed to randomly select a stop position of the variable symbol reel strip, select the symbol position associated with the randomly selected stop position, and populate the variable symbol position 105 with the game symbol 84 associated with the selected symbol position.

It should be noted that in one aspect of the present invention, one or more dynamic virtual reel strips may be utilized. Using virtual reel strips, the symbols and/or symbol positions and/or virtual reel strips and/or length or size and/or any aspect of a virtual reel strip may change from one spin or play to the next. For example, a dynamic reel strip includes a plurality of symbol positions with symbols from the symbol set and a plurality of variable symbol positions. The variable symbol positions may be in the form of one or more stacks, i.e., adjacent symbol positions. In one embodiment, the location and/or size of the stacks may change from one spin to the next, either randomly and/or in a predetermined pattern.

Alternatively, a virtual reel strip associated with a column of cells may be dynamically changed from one spin or play to another spin or play. This may occur randomly, every spin or play and/or in a predetermined pattern. It should be noted that in the illustrated embodiment, each column of the grid 80 has a corresponding reel. When the reel stops, a symbol from the respective reel appears in each one of the cells of the respective column of the grid 80.

In general, the control unit 20 starts an instance of the primary game 68 and determines the stop position of each virtual reels 70 to 78 randomly using a reel stop position data file 108 (shown in FIG. 12) stored in the memory device. The virtual reels 70 to 78 that are displayed in the display unit 14 (for example, the lower display 24) are moved from a current position and stopped based on a stop position to express an outcome of the primary game. Due to this, in the display or grid 80, the symbols included on the virtual reels 70 to 78 are continuously moved (scrolled or spun) in a vertical direction of the display area 64, and one symbol of one cell 82 is aligned in an order of the symbol based on the symbol arrangement is stopped so that it is displayed.

The control unit 20 changes and stops the plurality of symbols displayed on the display unit 14 according to the operation of the player received by the operation unit 32, and a payout may be paid according to the stopped symbols inside the display area 64 and a pay line set and payable data file 110 (shown in FIG. 13) stored in the memory device.

In the display area 64, a pay line is set that is used when winning is determined. The pay line is set to be extended over the column on the right end from the cells of the column of the left end and is a line that combines the plurality of cells 82 determining a win. The number of effective lines within the set pay line is selected by the operation of a group of line designation buttons included in the group of setting buttons 34 of the operation unit 32 for the player. The control unit 20, in regard to the result of a game that is a combination of symbols, determines a win when a predetermined number of identical symbols is surpassed and aligned on a set pay line, and pays a payout to the player according to the type and number of symbols. The system for determining a win may determine a win when a predetermined number of identical symbols from cells of the column on the left end are aligned on a set pay line, may determine a win when a predetermined number of identical symbols from cells of the column on the right end are aligned on a set pay line, and may determine a win when a predetermined number of

identical symbols are aligned on a continuous column on a predetermined pay line. It should be noted that pay lines shown other than (or in addition to) the pay lines shown in FIG. 13 may be used. In general, the pay lines start in the first column and end in the last column and include one cell per column. However, one or more pay lines could include one or more cells in the same column and may include a vertical pay line.

In some embodiments, upon detecting the occurrence of 10 the trigger condition occurring with the primary game, the control unit 20 executes a bonus feature event algorithm to display a bonus feature event. For example, upon detecting the occurrence of the trigger condition, the control unit 20 may display additional game symbols and/or game animations on the game screen and/or transitions the game screen 15 from the primary game to the bonus feature event.

Referring to FIGS. 5-8, in the illustrated embodiment, the memory 42 stores a game application program 200 that includes computer executable instructions that, when 20 executed by the processor 38, cause the processor 38 to generate and display the game on the display unit 14 of the gaming machine 10. In one embodiment, the game application program 200 includes program code 202 and program object data 204 that includes computer executable instructions 25 for implementing a game using the algorithms shown in FIG. 14.

In the illustrated embodiment, the memory 42 stores the game application program 200 and a system application program 206 that includes computer executable instructions that, when executed by the processor 38, cause the processor 38 to generate and display the game on the display unit 14 of the gaming machine 10. The game application program 200 provides game specific/front-end functions and the system application program 206 provides generic/back-end functions, when executed by the processor 38. In the illustrated embodiment, the game application program 200 and the system application program 206 are implemented on the same operating system. However, it should be noted that these programs may be implemented on different operating system and/or by different processors. In one embodiment, the game application program 200 includes a plurality of software modules including a bet/denomination/payline button listener module 208, a start button listener module 210, a credit balance manager module 212, a sampling manager 214, a random number generator 216, a comparison manager 218, a game result generator 220, a win evaluator 222, a game presenter 224, a game graphics presenter 226, a game sound presenter 228, a win indicator 230, an award provider 232, an application manager 234, and an external communicator 236. The game application program 200 may also include the reel strip data files, the symbol image data files, the variable symbol reel strip data files, the reel stop position data file, the credit prize symbol weight tables, the pay line set, and the payable data file.

The bet/denomination/payline button listener module 208 is a software module for receiving a signal from the bet button, the denomination button, or the payline button which is generated by the button when a player operates the button to select number of bet, denomination, or number of paylines. In response to receiving the signal, the bet/denomination/payline button listener module 208 communicates the occurrence of the signal to application manager 234 for changing bet, denomination, or payline configuration of the game.

The start button listener module 210 is a software module for receiving a signal from the start button which is generated by the button when a player operates the button to start

11

a game. In response to receiving the signal, the start button listener module 210 communicates the occurrence of the signal to application manager 234 for starting the game.

In response to receiving the signal from start button listener module 210, the application manager 234 requests the sampling manager 214 to obtain necessary number of random numbers from the random number generator 216.

The random number generator 216 generates random numbers based on predetermined algorithm of computational random generation method. The random number generator 216 may be a pseudorandom generator. In response to a request from sampling manager 214, the random number generator 216 returns random number. In some implementations, the random number generator 216 may be implemented in a central server. The random number generator 216 may be implemented as an integrated circuit or hard wired logic.

The comparison manager 218 compares the current state of the game or each random number with the reel strip data files, the symbol selection data files, the reel stop position data file, the pay line set, and/or the paytable data file and specifies corresponding reel layout, stop position, prize symbol, or trigger symbol based on each random number.

The game result generator 220 generates game result based on selected reel layout, stop positions of each reel, and bonus features.

The win evaluator 222 evaluates the game result with reference to the pay table. \

The game presenter 224 provides game presentation process with visual and sound so as to form the predetermined game result finally.

The game graphics presenter 226 provides visual game presentation process on the display so as to form the predetermined game result finally.

The game sound presenter 228 provides sound presentation process by using sound controller and speakers.

The win indicator 230 indicates win combinations and payment condition of prize symbol formed in the game result.

The award provider 232 provides award credit to win meter based on the win evaluation.

The application manager 234 administrates activity and status of each software module. In addition, the application manager 234 administrates configuration, progress and states of the game application program 200.

The external communicator 236 communicates instruction and data with the system application program 206.

The credit balance manager module 212 executes a process for decrementing credit balance and incrementing credit balance based on win amount displayed in win meter.

In the illustrated embodiment, the system application program 206 provides background processing and functions other than game specific functions. The system application program 206 includes a plurality of software modules including a system manager 238, a security manager 240, a slot management module 242, a denomination manager 244, a data logger 246, a communications manager 248, a bill acceptor manager 250, a metering module 252, and a cashout manager 254.

The system application program 206 may also include a game recall file 256, accounting logs 258, and meters 260.

The system manager 238 is a software module for administrating all of the background processing and functions other than game specific functions conducted by the system application program 206.

12

The security manager 240 is a software module for administrating game verification, door security and monitoring security sensors.

The slot management module 242 is a software module for administrating data accumulation and communicating with external slot information system 62.

The denomination manager 244 is a software module for establishing denomination setting of the gaming machine 10. The denomination setting may include 1 cent, 2 cent, 5 cent, 25 cent, 1 dollar, 5 dollar and the like.

The data logger 246 is a software module for logging result of each primary game and the free game bonus to the game recall. In addition, the data logger 246 stores error events, bill log, cashout log, ticket log etc. to the accounting log.

The game recall file 256 is an accumulated data including results of each primary game and free game bonus. The game recall file 256 is stored in a non-volatile memory.

The accounting logs 258 is an accumulated data including error events, bill log, cashout log, ticket log etc. The accounting logs 258 are stored in a non-volatile memory.

The communications manager 248 is a software module for administrating communication between game application program 200 and system application program 206. The communications manager 248 also administrates network communication between system application program 206 and external network such as slot management system network, G2S network, gaming server for server based gaming network or VLT system network.

The bill acceptor manager 250 is a software module for administrating the bill acceptor and receives bill information inserted in the bill acceptor. In response to receiving the information from the bill acceptor, the bill acceptor manager 250 communicates with the metering for incrementing credit balance based on the inserted bill.

The metering module 252 is a software module for adjusting values of the meters 260 in response to communication with the game application program 200 via communications manager 248, the bill acceptor manager 250 or the cashout manager 254. The meters 260 includes a credit meter for indicating current credit balance on the gaming machine and a win meter for indicating win amount of current game session. The meters further include background meters such as coin-in, coin-out, total drop, attendant paid jackpots and/or bill-in. These meters might be implemented as data on the non-volatile memory or hardware meters.

The cashout manager 254 is a software module for administrating cashout procedure. In response to a player's operation on the cashout button, the cashout manager 254 is activated and the gaming machine pay total amount of the credit meter.

Referring to FIGS. 9 and 10, in one embodiment, the present invention includes a networked server computer system 300 that is configured to deliver the game to one or more client computing devices 302 over the Internet. In the illustrated embodiment, the networked computer system 300 includes an iGaming server system 304 that is coupled in communication with one or more client computing devices 302 via a communications network 306. The communications network 306 may be any suitable connection, including the Internet, an Intranet, LAN, a virtual private network (VPN), cellular networks, etc. . . . , and may utilize any suitable or combination of technologies including, but not limited to wired and wireless connections, always on connections, connections made periodically, and connections made as needed.

The client computing device 302 may include any suitable device that enables a user to access and communicate with the server system 300 including sending and/or receiving information to and from the server system 300 and displaying information received from the server system 300 to a user. In the illustrated embodiment, the client computing device 302 includes a processor coupled to a memory device. The memory device stores various programs and data that are executed by the processor for operating the client computing device 302. The client computing device 302 also includes an input device configured to receive operational inputs from the user, and a display device configured to display a graphical user interface. The input device and display device enable a user to interact with the server system 300 via the client computing device 302. For example, in one embodiment, the client computing device 302 may include, but is not limited to, a desktop computer, a laptop or notebook computer, a tablet computer, smartphone/tablet computer hybrid, a personal data assistant, a handheld mobile device including a cellular telephone, and the like. In one embodiment, the processor of the client computing device 302 may be programmed to function as the control unit 22 of the gaming machine 10.

In the illustrated embodiment, the client computing device may include a web browser program stored in the memory device. The processor executes the web browser program to display web pages on the display device that includes information received from the server system 300 to enable a user to interact with and operate the server system 300.

In one embodiment, the client computing device 302 includes a mobile computing device 308 (shown in FIG. 10) such as, for example, a tablet computer, a smartphone/tablet computer hybrid, a smartphone such as an iPhone™, and the like. The mobile computing device 308 includes a processor coupled to a memory device for storing various programs and data for use in operating the mobile computing device 308. The mobile computing device 308 may also include a display unit 14 including a touchscreen, one or more video image cameras, one or more speakers, a microphone, at least one input button, and one or more sensors including, but not limited to, a touch ID fingerprint sensor coupled to an input button, a barometer, a three-axis gyro, an accelerometer, proximity sensor, and an ambient light sensor. In addition, the mobile computing device 308 may also include a Wi-Fi antenna, a cellular network antenna, a Bluetooth™ communications device, assisted GPS and GLONASS, a digital compass, and an iBeacon™ microlocation device.

The mobile computing device 308 may be programmed to store and execute mobile computer program applications that display graphical user interfaces on the touchscreen display unit 14 including display area 64 that allows the user to access the server system 300 to retrieve and store information within the server system 300 as well as interact with and operate the server system 300. In addition, in one embodiment, the server system 300 may install one or more mobile computer application programs in the memory device of the mobile computing device 308. When initiated by the processor of the mobile computing device 308, the mobile computer application program causes the processor of the mobile computing device 308 to perform some or all of the functions of the gaming machine 10.

In the illustrated embodiment, the server system 300 includes one or more remote gaming servers 310, one or more back-end servers 312, one or more real money gaming website hosting servers 314, and one or more social gaming website hosting servers 316. In the illustrated embodiment,

the social gaming website hosting server 316 and the real money gaming website hosting server 314 are programmed to host a website that is accessible by a user via one or more client computing devices 302. The website hosting servers 314 and 316 execute a website application program that retrieves application code from the back-end server 312 and executes the application code to render one or more webpages on a display device of a client computing device 302 in response to requests received from the user via the client computing device 302 to allow users to interact with the website. The website hosting servers 314 and 316 are configured to generate and display webpages displaying a game. For example, the real money gaming website hosting server 314 is configured to host a real money wagering website that enables players to convert monetary funds to gaming credits that may be used to place wagers on the game. The social gaming website hosting server 316 is configured to host a social media and/or social gaming website that allows players to receive gaming credits for activities such as purchasing goods and/or services through an e-commerce website, and/or purchase gaming credits that may be used to play the game.

Each back-end server 312 is configured to perform operations to support the functions of the webpages and/or website being displayed by the website hosting servers 314 and 316. For example, in one embodiment, the back-end servers 312 may include a player account system server that is configured to generate player accounts that include data associated with a player including, but not limited to, player identification information, player financial account information, player gaming credit account information, and/or any suitable player information, that may be used to establish credit meters and allow players to place wagers on the game.

Each remote gaming server 310 includes one or more copies of the game application program 200 stored in a memory device of the remote gaming server 310. A processor of the remote gaming server 310 is programmed to retrieve and transmit the game application program 200 to one or more back-end servers 312 for use in displaying the game to the user via a webpage being displayed by the web browser program.

In one embodiment, the game application program 200 may include instructions for rendering the game and executing the game on the client computing device 302. For example, the game application program 200 may include instructions for generating rendered code, such as, for example HTML code, which may be used by the web browser program of the client computing device 302 for displaying the game. For example, the game application program 200 may include program software code including, but not limited to, HTML, JavaScript, cascade style sheets (CSS), and any suitable programming code that may be used for rendering and operating the game via a website and/or mobile computer application.

In one embodiment, upon receiving a request from the website hosting servers 314, 316 via the back-end server 312, the remote gaming server 310 may execute the game application program 200 to operate the game and execute a render-to-string operation to generate rendered code indicative of the game, such as, for example HTML code, and transmit the rendered code to the back-end server 312. The back-end server 312 may then transmit the rendered code to the corresponding website hosting servers 314, 316 for use in displaying the game on the website. As the player plays the game, the remote gaming server 310 may execute the game application program 200 for each instance of the game, and transmit rendered code to the back-end servers 312.

In another embodiment, the remote gaming server 310 may transmit the game application program 200 to the back-end server 312 and/or the website hosting servers 314, 316. The back-end server 312 and/or the website hosting servers 314, 316 may then execute the game application program 200 to initiate the instances of the game and execute render-to-string operations to generate rendered code indicative of the game.

In yet another embodiment, the back-end server 312 may receive a request to initiate the game from a mobile computing device 308 executing the mobile computer application program. Upon receiving the request, the back-end server 312 may access the game application program 200 and execute a render-to-string operation to generate rendered code indicative of the game and transmit the rendered code to the mobile computing device 308. In one embodiment, the back-end server 312 may continuously execute the game application program 200 to generate each instance of the game using a random number generator of the back-end server 312 based on input received from the mobile computing device 308 and generate and transmit rendered code for each instance of the game to the mobile computing device 308. In another embodiment, the back-end server 312 may execute a partial-render operation and generate partially-rendered code of the game using the game application program 200 and transmit the partially rendered code of the game and object data of game assets to the mobile computing device 308. The partially rendered code includes instructions for generating rendered code using the game assets and a random number generator of the mobile computing device for generating and displaying the game on the mobile computing device 308 using the mobile computer application program.

In one embodiment, the game application program 200 may be stored on several different servers. The game code on these servers is used to distribute game content to social or real money gaming websites and mobile applications. The distribution method is very flexible. For example, the game code and/or game application program 200 including game code and game object assets may be stored on a remote gaming server 310. One remote gaming server 310 may be connected to one or more back-end server 312.

Each back-end server 312 is configured to distribute the games to one or more websites or mobile applications. Players connect to these websites/mobile applications with the client devices or mobile devices and have access to the game content. A copy of game application program 200 including game code and game object assets is stored on the remote gaming server 310 for each back-end server 312 that is connected to the remote gaming server 310 and that distributes the game. For example, if one remote gaming server 310 is connected to two back-end servers 312, which is connected to three website hosting servers 314, 316 that distribute the game, the remote gaming server 310 would store two copies of the game application program 200 including game code and game object assets for the game (e.g., one copy for each back-end server 312).

For example, the server system 300 may be configured to implement the game on a mobile application such as, for example, "my KONAMI Slots™" mobile application available in Apple iOS™, Google Android™, and Amazon Kindle™ operating platforms, or on social-media websites such as the "my KONAMI Slots™" available on Facebook™. In one embodiment, the mobile application may download the game code from remote gaming server 310 via the real money gaming site 314 or the social gaming site 316 and execute the game code on the client computing device

302. In this embodiment, the game code may provide game specific/front-end function when executed by the processor of the client computing device, and the back end system 312 may provide generic/back-end function.

5 FIG. 14 is a flow chart of method 400 illustrating the algorithms included in the game application program 200 and performed by the processor 38 when executing the game application program 200 for operating the gaming machine 10 and/or iGaming server system 300 to implement the 10 game. The methods include a plurality of steps. Each method 15 step may be performed independently of, or in combination with, other method steps. Portions of the methods may be performed by any one of, or any combination of, the components of the gaming machine 10 and/or iGaming server system 300.

In the illustrated embodiment, the game application program 200 includes computer instructions for generating the primary game 68 and the bonus feature event. In general, the bonus feature event is executed when a triggering event is 20 detected during the primary game 68. In one embodiment, the primary game 68 includes a reel-type game that includes a plurality of virtual reels that spin and stop to display the 25 outcomes of the primary game. In other embodiments, the primary game 68 may include a playing card game, a bingo game, a Keno game, and/or any suitable casino type wagering game.

In the illustrated embodiment, the control unit 20 is programmed to execute the algorithm illustrated in method 30 400 for executing the game and displaying the game on the 35 display unit 14. In method step 402, the processor 38 of the control unit 20 generates the virtual reels 70-78 for use with an instance of the primary game 68 and displays the virtual 40 reels 70-78 in the grid 80.

In method step 404, the processor 38 receives a signal to 35 initiate an instance of the game 66 and generates the virtual 40 reels 70-78 for use during the instance of the game 66. For example, the processor 38 may receive a signal from the display unit 14 and/or the operation unit 32 indicating a 45 player's request to initiate an instance or play of the game 66. In one embodiment, the player may transmit a request to 50 initiate an instance or play of game 66 by depressing a corresponding "spin" button on the operation unit 32 by touching a corresponding button icon being displayed on a 55 touchscreen of the display unit 14. Upon receiving a signal from the display unit 14 and/or the operation unit 32, the processor 38 initiates the instance of the game 66 by generating the virtual 60 reels 70-78 for use in the primary game 68.

In method steps 406-416, the processor 38 randomly 50 determines an outcome of an instance of the primary game 68 and spins the virtual reels 70 to 78 and sequentially stops the virtual reels 70 to 78 to display the randomly generated 55 outcome including a game symbol being displayed in each cell 82 of the grid 80. For example, in one embodiment, the processor 38 starts spinning each virtual reel 70 to 78, obtains random numbers from the random number generator, and determines a stop position of each virtual reel 70 to 60 78 based on the random numbers and the reel stop position data file 108. In the illustrated embodiment the reel stop position data file 108 includes a range of random numbers associated with each symbol position in the sequence of symbol positions associated with the virtual reel. In one embodiment, the processor may obtain a random number for each simulate virtual reel 70 to 78, i.e., five random numbers. The processor 38 then establishes a reel stop counter, "i", and sets the reel stop counter, i, equal to 1. The processor 38 then identifies the ith virtual reel strip associated with the 65

stop counter, i , and stops the identified virtual reel strip to display the corresponding symbols in the corresponding cells 82 associated with the identified virtual reel strip. The processor 38 then increments the reel stop counter, i , by 1, i.e., $i=i+1$, and repeats the process of identifying the virtual reel strip associated with the incremented reel stop counter and stopping the identified virtual reel. This process continues until each virtual reel has been stopped. In this embodiment, for example, the virtual reels are numbered 1-5. In one embodiment, during the reel spin, the player may initiate the stopping of the reels by depressing the spin button, which enables the player to accelerate game play.

In method step 418, the processor 38 determines whether a trigger condition has been detected in the outcome of the primary game 68. If a trigger condition is detected during the primary game 68, the processor 38 initiates the bonus feature event in method step 420.

In method step 422, upon completion of the primary game 68 and/or the bonus feature event, the processor 38 determines and provides any award associated with the outcome of the primary game 68 and/or the bonus feature event. For example, the processor 38 may determine whether any winning combination of symbols is displayed in the outcome of the instance of the primary game 68 and/or the bonus feature event provide an award by increasing a balance of the credit meter based on the amount of the award.

FIG. 15 is a flow chart of method 500 illustrating the algorithms included in the game application program 200 and performed by the processor 38 when executing the game application program 200 for operating the gaming machine 10 and/or iGaming server system 300 to implement the game. The methods include a plurality of steps. Each method step may be performed independently of, or in combination with, other method steps. Portions of the methods may be performed by any one of, or any combination of, the components of the gaming machine 10 and/or iGaming server system 300.

In the illustrated embodiment, as shown in FIGS. 15-22, the game application program 200 includes computer instructions for providing the Wheel Boost 7s^{TM} slot game feature offered by Konami Gaming^{TM} Inc. The Wheel Boost 7s^{TM} slot game feature includes a bonus wheel 112 containing credit prizes, jackpot prizes and Free Games. A bonus wheel feature 114 is triggered by collecting a predefined number of bonus wheel symbols 116 in a bonus wheel meter 118. Bonus wheel symbols 116 appear on the reels 70-78 randomly. Bonus wheel symbols 116 may also appear on the bonus wheel 112. Thus, during the bonus wheel feature 114 the player can start collecting towards the next Bonus Wheel Feature (and this will reduce zero persistence states that make walking away easy). Bonus wheel symbols 116 appearing on the bonus wheel 112 may also have credit prizes awarded.

Bonus wheel upgrade symbols 120 also appear on the reels 70-78 randomly. When a bonus wheel upgrade symbol 120 lands on the reels 70-78, the bonus wheel upgrade symbol 120 upgrades one of the prizes on the bonus wheel 112. The bonus wheel wedge that is upgraded is randomly chosen. The upgrade amount may be fixed to schedule (Ex: 1x, 2x, 3x, etc.), or may be randomly selected. The upgrade can happen to any of the prizes on the bonus wheel. For example, the upgrade will increase the value of credit prizes and jackpot prizes, while increasing the number of Free Games on Free Games prize. The Upgraded Prize will have a visual change to easily convey that it has been upgraded. Upgraded Prizes will remain upgraded until they are awarded. Prizes can be upgraded more than once.

Extra wheel spin symbols 122 also appear on the reels 70-78 randomly. Extra wheel spin symbols 122 will increase the number of bonus wheel spins by 1. The number of extra wheel spins will be applied when the Bonus wheel feature 114 is triggered. In some embodiments, up to 5 wheel-spins may be awarded during the bonus wheel feature 114.

The processor 38 may be programmed to provide a free game feature. For example, the appearance of the bonus wheel upgrade symbol 120 on the reels 70-78 may increase 10 the number of free games, e.g., free reel spins. More coins may appear in free games.

As shown in FIGS. 15-22, in method step 502, the processor 38 displays the game 66 on the game screen 64 including a plurality of reels 70, 72, 74, 76, 78 displaying a 15 plurality of game symbols 84. The reels 70-78 are displayed in the grid 80 including a plurality of cells 82 arranged in a plurality of rows (r) and a plurality of columns (c). In some embodiment, the game 66 may include 5 reels with each reel being displayed in a corresponding column (c). The processor 38 also displays a bonus wheel 112 on the game screen 64 positioned above the plurality of reels 70-78. The bonus wheel 112 includes a plurality of wheel wedges 124 displaying a plurality of prize symbols 126 and a prize selector 128. During the bonus wheel feature 114, the processor 38 20 may spin and stop the bonus wheel 112 to display a prize symbol 126 adjacent to the prize selector 128 and award the corresponding prize symbol 126 to the player (e.g., increase the credit meter based on the prize symbol 126 displayed adjacent to the prize selector 128 when the bonus wheel 112 25 is stopped).

In the illustrated embodiment, the processor 38 also displays a bonus wheel meter 118 on the game screen 64. The bonus wheel meter 118 includes a number of bonus wheel symbols 116 that are collected during spins of the 30 reels 70-78. The processor 38 may initiate the bonus wheel feature 114 when a predefined number of bonus wheel symbols 116 have been collected in the bonus wheel meter 118. For example, the processor 38 may require five bonus wheel symbols 116 to be collected in the bonus wheel meter 35 118 before the bonus wheel feature 114 is triggered and initiated. The processor 38 may also be programmed to display the bonus wheel meter 118 above the reels 70-78 and to include a collection of bonus wheel symbols 116 to allow the 40 player to easily recognize the bonus wheel meter 118 and to identify the number of bonus wheel symbols 116 currently included in the bonus wheel meter 118.

The processor 38 may also be programmed to display an extra wheel spin meter 130 on the game screen 64. The extra wheel spin meter 130 indicates a number of extra wheel spins of the bonus wheel 112 that will be implemented by the processor 38 during the bonus wheel feature 114. In the illustrated embodiment, the extra wheel spin meter 130 is displayed above the bonus wheel meter 118 and includes a collection of the extra wheel spin symbol 122 to allow the 45 player to easily recognize the number of extra wheel spins of the bonus wheel 112 that will be awarded to the player if the bonus wheel feature 114 is triggered.

In method step 504, the processor 38 spins and stops the reels 70-78 to display an instance of the game 66. For 50 example, in one embodiment, the processor 38 may access the reel strip data files 88 to generate each virtual reel 70 to 78, prior to initiating a spin of the reels 70-78 to display an instance of the game 66. The processor 38 may identify each variable symbol position 105 appearing in the reel strips 55 94-102 and access a variable symbol reel strip data file 132 (shown in FIG. 16) for use in selecting a symbol to display in each variable symbol position 105. For example, the

variable symbol reel strip data file 132 may include a plurality of special wheel symbols 134 and selection weight associated with each special wheel symbol 134. Each special wheel symbol 134 is associated with instructions that cause the processor 38 to initiate a feature event that is associated with the bonus wheel feature 114. For example, in the illustrated embodiment, the plurality of special wheel symbols 134 includes a bonus wheel symbol 116, a bonus wheel upgrade symbol 120, and an extra wheel spin symbol 122. The appearance of the bonus wheel symbol 116 on the reels 70-78 in an outcome of the game 66 causes the processor 38 to increase the number of bonus wheel symbols 116 that are collected and displayed in the bonus wheel meter 118.

The appearance of the bonus wheel upgrade symbol 120 on the reels 70-78 in an outcome of the game 66 causes the processor 38 to randomly select a wheel wedge 124 displayed on the bonus wheel 112 and upgrade a corresponding prize symbol 126 displayed with the selected wheel wedge 124. Upon detecting the appearance of the bonus wheel upgrade symbol 120, the processor 38 may also increase the number of bonus wheel symbols 116 that are collected and displayed in the bonus wheel meter 118.

The appearance of the extra wheel spin symbol 122 on the reels 70-78 in an outcome of the game 66 causes the processor 38 to increase the number of extra wheel spins indicated by the extra wheel spin meter 130. Upon detecting the appearance of the extra wheel spin symbol 122, the processor 38 may also increase the number of bonus wheel symbols 116 that are collected and displayed in the bonus wheel meter 118.

By using the variable symbol reel strip data file 132 to randomly select special wheel symbols 134 to populate the variable symbol positions 105 appearing in the reel strips 94-102, the processor 38 is able to vary the type special wheel symbols 134 (e.g., the bonus wheel symbol 116, the bonus wheel upgrade symbol 120, and the extra wheel spin symbol 122) appearing in the reels 70-78 for each instance of the game 66, and to vary the amount of bonus wheel symbols 116, bonus wheel upgrade symbols 120, and extra wheel spin symbols 122 that appear in the reels 70-78.

Once the reels 70-78 have been generated, the processor 38 then initiates an instance of the game 66 by animating the reels 70-78 on the game screen 64 to simulate the reels 70-78 spinning and stopping.

In method step 506, upon stopping the reels 70-78, the processor 38 determines whether one or more bonus wheel symbols 116 appear in the reels 70-78 with the reels 70-78 stopped. Upon detecting an appearance of one or more bonus wheel symbols 116 appearing in the reels 70-78 with the reels 70-78 stopped, the processor 38 executes method step 508 to increase the number of bonus wheel symbols 116 included in the bonus wheel meter 118 based on the detected bonus wheel symbols 116. As shown in FIG. 19, for each bonus wheel symbol 116 appearing in the reels 70-78, the processor 38 animates a copy of the bonus wheel symbol 116 appearing in the reels 70-78 to move onto the bonus wheel meter 118 to increase the number of bonus wheel symbols 116 collected in the bonus wheel meter 118. If multiple bonus wheel symbols 116 appear in the reels 70-78 with the reels 70-78 stopped, the processor 38 will animate a copy of each of the bonus wheel symbols 116 to move from the reels 70-78 onto the bonus wheel meter 118 in a sequential order.

The processor 38 then initiates method step 510 to determine whether one or more bonus wheel upgrade symbols 120 appear in the reels 70-78 with the reels 70-78 stopped. Upon detecting an appearance of one or more bonus wheel upgrade symbols 120 appearing in the reels 70-78 with the

reels 70-78 stopped, the processor executes method step 512 to upgrade a prize symbol 126 appearing on the bonus wheel 112. For example, the processor 38 randomly selects a wheel wedge 124 displayed on the bonus wheel 112 and upgrades a corresponding prize symbol 126 displayed with the selected wheel wedge 124. In some embodiment, the processor 38 may access a bonus wheel data file 136 (shown in FIG. 17) that includes instructions associated with generating prize symbols 126 being displayed on the bonus wheel 112. For example, the bonus wheel data file 136 may include instructions associated with each wheel wedge 124 including a wheel wedge ID and a selection weight associated with each wheel wedge. The bonus wheel data file 136 may also include instructions for displaying an initial prize symbol 126 for each wheel wedge 124. When upgrading the bonus wheel 112 the processor 38 may access the bonus wheel data file 136 and randomly select a wheel wedge 124 based on the corresponding selection weights and upgrade the prize symbol 126 currently displayed in the randomly selected wheel wedge 124. In one embodiment, the processor 38 may upgrade the current prize symbol 126 by a based on a fixed schedule (e.g., 1x, 2x, 3x multiplier, etc.). In other embodiments, the processor 38 may randomly select an upgrade such as, for example, a credit prize multiplier, progressive prize upgrade, and/or upgrade the wheel wedge to include special wheel symbols 134 (e.g., the bonus wheel symbol 116, the bonus wheel upgrade symbol 120, and the extra wheel spin symbol 122).

Upon detecting an appearance of one or more bonus wheel upgrade symbols 120 appearing in the reels 70-78, the processor 38 also executes method step 514 to increases the number of bonus wheel symbols 116 included in the bonus wheel meter 118 based on the detected bonus wheel upgrade symbol 120. For example, if two bonus wheel upgrade symbols 120 appear in the reels 70-78, the processor 38 will select two wheel wedges 124 to be upgraded and adds two bonus wheel symbols 116 to the bonus wheel meter 118. As shown in FIGS. 20-21, for each bonus wheel upgrade symbol 120 appearing in the reels 70-78, the processor 38 animates a copy of the bonus wheel upgrade symbol 120 appearing in the reels 70-78 to move onto the bonus wheel meter 118 to increase the number of bonus wheel symbols 116 collected in the bonus wheel meter 118 and animates an upgrade symbol (e.g., a copy of the bonus wheel upgrade symbol 120 shown in FIG. 20, or a “rocket” symbol shown in FIG. 21) to move onto the randomly selected wheel wedge 124 to upgrade the prize symbol 126 displayed in selected wheel wedge 124.

The processor 38 then initiates method step 516 to determine whether one or more extra wheel spin symbols 122 appear in the reels 70-78 with the reels 70-78 stopped. Upon detecting an appearance of one or more extra wheel spin symbols 122 appearing in the reels 70-78 with the reels 70-78 stopped, the processor 38 initiates method step 518 to increase the number of extra wheel spins indicated by the extra wheel spin meter 130 based on the detected extra wheel spin symbol 122 and initiates method step 520 to increase the number of bonus wheel symbols 116 included in the bonus wheel meter 118 based on the detected extra wheel spin symbol 122. As shown in FIG. 22, for each extra wheel spin symbols 122 appearing in the reels 70-78, the processor 38 animates copies of the extra wheel spin symbol 122 to the bonus wheel meter 118 and to the extra wheel spin meter 130. For example, the processor 38 animates a copy of the extra wheel spin symbol 122 appearing in the reels 70-78 to move onto the extra wheel spin meter 130 to increases the number of extra wheel spins indicated by the

extra wheel spin meter 130 and animates a copy of the extra wheel spin symbol 122 appearing in the reels 70-78 to move onto the bonus wheel meter 118 to increase the number of bonus wheel symbols 116 collected in the bonus wheel meter 118. If multiple extra wheel spin symbols 122 appear in the reels 70-78 with the reels 70-78 stopped, the processor 38 will animate a copy of each of the extra wheel spin symbols 122 to move from the reels 70-78 onto the extra wheel spin meter 130 and the bonus wheel meter 118 in a sequential order.

In method step 522, processor 38 determines whether to initiate the bonus wheel feature 114. For example, the processor 38 may be programmed to initiate the bonus wheel feature 114 including a spin of the bonus wheel 112 upon determining that the increased number of bonus wheel symbols 116 included in the bonus wheel meter 118 is equal to a predefined number of bonus wheel symbols 116. For example, the processor 38 may initiate the bonus wheel feature 114 when five bonus wheel symbols 116 have been collected in the bonus wheel meter 118.

When initiating the bonus wheel feature 114, the processor 38 executes method step 524 and determines a number of extra wheel spins indicated by the extra wheel spin meter 130. The processor 38 then initiates an initial spin of the bonus wheel 112 to display an initial prize symbol 126 adjacent the prize selector 128 and initiates a number of additional spins of the bonus wheel 112 based on the number of extra wheel spins indicated by the extra wheel spin meter 130. Each additional spin of the bonus wheel 112 displays an additional prize symbol 126 adjacent the prize selector 128 that is awarded to the player. For example, if the extra wheel spin meter 130 indicates three extra spins are to be provided (shown as “+3 extra spins” in FIG. 22), when the processor 38 initiates the initiating the bonus wheel feature 114, the processor 38 will provide 4 spins (1 initial spin and 3 extra spins) of the bonus wheel 112 and award the player a prize symbol 126 for each of the 4 spins.

The processor 38 may also reset the bonus wheel meter 118 to include an initial number of bonus wheel symbols 116 upon initiating the bonus wheel feature 114. The initial number of bonus wheel symbols 116 may include a minimum amount of bonus wheel symbols 116 or no amount of bonus wheel symbols 116 (e.g., zero bonus wheel symbols 116). In some embodiments, the processor 38 may display the bonus wheel 112 with a wheel wedge 124 displaying another bonus wheel symbol 116. The processor 38 may then initiate a spin of the bonus wheel 112 and increase the number of bonus wheel symbols 116 included in the bonus wheel meter 118 upon detecting an appearance of the another bonus wheel symbol 116 adjacent the prize selector 128 with the bonus wheel 112 stopped.

In some embodiments, if an upgraded prize symbol 126 has been selected by the bonus wheel 112 (i.e., an upgraded prize symbol 126 appears adjacent the prize selector 128 with the bonus wheel 112 stopped) the processor 38 may reset corresponding wheel wedge 124 to display an initial prize symbol 126. For example, during the bonus wheel feature 114, if an upgraded prize symbol 126 appears adjacent the prize selector 128 and is awarded to the player, the processor 38 may access the bonus wheel data file 136 to retrieve instructions for displaying an initial prize symbol 126 for the corresponding wheel wedge 124 and animate the corresponding wheel wedge 124 to display the corresponding initiate prize symbol 126 indicated by the bonus wheel data file 136.

The bonus wheel feature 114 is triggered by collecting a predefined number of bonus wheel symbols 116 in a bonus

wheel meter 118. Bonus wheel symbols 116 appear on the reels 70-78 randomly. Bonus wheel symbols 116 may also appear on the bonus wheel 112. Thus, during the bonus wheel feature 114, the player can start collecting towards the next Bonus Wheel Feature. In this way, the processor 38 reduces zero persistence states for the Bonus Wheel Feature and increases the players interest in the game.

Exemplary embodiments of a gaming device, a gaming system, and a method of providing an award to a player are 10 described above in detail. The gaming device, system, and method are not limited to the specific embodiments described herein, but rather, components of the gaming device and/or system and/or steps of the method may be utilized independently and separately from other components and/or steps described herein. For example, the gaming device may also be used in combination with other gaming systems and methods and is not limited to practice with only the gaming device as described herein. Rather, an exemplary embodiment can be implemented and utilized in 15 connection with many other gaming system applications.

A controller, computing device, or computer, such as 20 described herein, includes at least one or more processors or processing units and a system memory. The controller typically also includes at least some form of computer readable media. By way of example and not limitation, computer readable media may include computer storage media and communication media. Computer storage media may include volatile and nonvolatile, removable and non-removable media implemented in any method or technology 25 that enables storage of information, such as computer readable instructions, data structures, program modules, or other data. Communication media typically embody computer readable instructions, data structures, program modules, or other data in a modulated data signal such as a carrier wave or other transport mechanism and include any information delivery media. Those skilled in the art should be familiar with the modulated data signal, which has one or more of its 30 characteristics set or changed in such a manner as to encode information in the signal. Combinations of any of the above 35 are also included within the scope of computer readable media.

The order of execution or performance of the operations 40 in the embodiments of the invention illustrated and described herein is not essential, unless otherwise specified. 45 That is, the operations described herein may be performed in any order, unless otherwise specified, and embodiments of the invention may include additional or fewer operations than those disclosed herein. For example, it is contemplated that executing or performing a particular operation before, contemporaneously with, or after another operation is within the 50 scope of aspects of the invention.

In some embodiments, a processor, as described herein, includes any programmable system including systems and microcontrollers, reduced instruction set circuits (RISC), 55 application specific integrated circuits (ASIC), programmable logic circuits (PLC), and any other circuit or processor capable of executing the functions described herein. The above examples are exemplary only, and thus are not intended to limit in any way the definition and/or meaning 60 of the term processor.

This written description uses examples to disclose the invention, including the best mode, and also to enable any person skilled in the art to practice the invention, including making and using any devices or systems and performing 65 any incorporated methods. The patentable scope of the invention is defined by the claims, and may include other examples that occur to those skilled in the art. Other aspects

23

and features of the present invention can be obtained from a study of the drawings, the disclosure, and the appended claims. The invention may be practiced otherwise than as specifically described within the scope of the appended claims. It should also be noted that the steps and/or functions listed within the appended claims, notwithstanding the order of which steps and/or functions are listed therein, are not limited to any specific order of operation.

Although specific features of various embodiments of the invention may be shown in some drawings and not in others, this is for convenience only. In accordance with the principles of the invention, any feature of a drawing may be referenced and/or claimed in combination with any feature of any other drawing.

What is claimed is:

1. A gaming machine for displaying computer-generated images associated with a game, comprising:

a cabinet;
a display device mounted to the cabinet and including a graphical user interface (GUI) display screen displaying computer-generated images thereon;
a control unit operably coupled to the display device, the control unit including a random number generator, a memory device storing computer-executable instructions, and a processor programmed to execute the computer-executable instructions to perform an algorithm to display an animated sequence of computer-generated images on the display device GUI including the steps of:

generating a plurality of virtual reels by:

accessing a reel strip data file stored in the memory device including computer-executable instructions associated with each virtual reel including a plurality of reel strips including a plurality of fixed symbol positions and at least one reel strip including a variable symbol position;

accessing a variable symbol reel strip data file stored in the memory device including computer-executable instructions associated with the variable symbol position including a plurality of special wheel symbols and associated selection weights;

randomly selecting a special wheel symbol from the plurality of special wheel symbols using the random number generator;

populating each fixed symbol position with a corresponding game symbol; and

populating the variable symbol position with the randomly selected special wheel symbol;

displaying a game screen on the display device GUI including the plurality of virtual reels displaying a plurality of game symbols, a bonus wheel positioned above the plurality of virtual reels and including a plurality of wheel wedges displaying prize symbols and a prize selector, and a bonus wheel meter displayed above the virtual reels and including a number of bonus wheel symbols;

animating the virtual reels to simulate spinning and stopping the virtual reels to display an instance of the game including a bonus wheel symbol and a bonus wheel upgrade symbol appearing in the virtual reels with the virtual reels stopped;

animating a copy of the bonus wheel symbol to move from the virtual reels to appear on the bonus wheel meter to increase the number of bonus wheel symbols displayed in the bonus wheel meter;

24

accessing a bonus wheel data file including computer-executable instructions associated with each wheel wedge including a wheel wedge ID and an associated selection weight;

randomly selecting a wheel wedge displayed on the bonus wheel based on the associated selection weights using the random number generator;

modifying the bonus wheel by transforming a corresponding prize symbol displayed with the randomly selected wheel wedge to display an upgraded prize symbol; animating a copy of the bonus wheel upgrade symbol to move from the virtual reels to appear on the bonus wheel meter; and

animating the bonus wheel to spin and stop upon determining the increased number of bonus wheel symbols included in the bonus wheel meter is equal to a predefined number of bonus wheel symbols.

2. The gaming machine of claim 1, wherein the processor is programmed to execute the algorithm including the steps of:

randomly selecting the upgraded prize symbol from the bonus wheel data file that includes instructions associated with generating prize symbols being displayed on the bonus wheel.

3. The gaming machine of claim 1, wherein the processor is programmed to execute the algorithm including the steps of:

displaying the bonus wheel with a wheel wedge displaying another bonus wheel symbol; and

initiating the spin of the bonus wheel and increasing the number of bonus wheel symbols included in the bonus wheel meter upon detecting an appearance of the another bonus wheel symbol adjacent the prize selector with the bonus wheel stopped.

4. The gaming machine of claim 1, wherein the processor is programmed to execute the algorithm including the steps of:

displaying an extra wheel spin meter on the game screen indicating a number of extra wheel spins; and

initiating the bonus wheel feature by:

initiating an initial spin of the bonus wheel to display an initial prize symbol adjacent the prize selector; and initiating a number of additional spins of the bonus wheel based on a number of extra wheel spins indicated by the extra wheel spin meter, each additional spin of the bonus wheel displaying an additional prize symbol adjacent the prize selector.

5. The gaming machine of claim 4, wherein the processor is programmed to execute the algorithm including the steps of:

detecting an appearance of an extra wheel spin symbol appearing in the virtual reels with the virtual reels stopped and increasing the number of extra wheel spins indicated by the extra wheel spin meter based on the detected extra wheel spin symbol; and

increasing the number of bonus wheel symbols included in the bonus wheel meter based on the detected extra wheel spin symbol.

6. The gaming machine of claim 4, wherein the processor is programmed to execute the algorithm including the steps of:

animating copies of the extra wheel spin symbol to the bonus wheel meter and to the extra wheel spin meter.

7. The gaming machine of claim 1, wherein the processor is programmed to execute the algorithm including the steps of:

25

resetting the bonus wheel meter to include an initial number of bonus wheel symbols upon initiating the bonus wheel feature.

8. The gaming machine of claim 1, wherein the processor is programmed to execute the algorithm including the steps of:

animating a copy of the bonus wheel symbol appearing in the virtual reels to the bonus wheel meter to increase the number of bonus wheel symbols included in the bonus wheel meter.

9. A method of operating a gaming machine including a display device mounted to a cabinet and including a graphical user interface (GUI) display screen displaying computer-generated images thereon, and a control unit including a random number generator, a memory device storing computer-executable instructions, and a processor operably coupled to the display device, the method including the processor performing an algorithm to display an animated sequence of computer-generated images on the display device GUI including the steps of:

generating a plurality of virtual reels by:

accessing a reel strip data file stored in the memory device including computer-executable instructions associated with each virtual reel including a plurality of reel strips including a plurality of fixed symbol positions and at least one reel strip including a variable symbol position;

accessing a variable symbol reel strip data file stored in the memory device including computer-executable instructions associated with the variable symbol position including a plurality of special wheel symbols and associated selection weights;

randomly selecting a special wheel symbol from the plurality of special wheel symbols using the random number generator;

populating each fixed symbol position with a corresponding game symbol; and

populating the variable symbol position with the randomly selected special wheel symbol;

displaying a game screen on the display device GUI including the plurality of virtual reels displaying a plurality of game symbols, a bonus wheel positioned above the plurality of virtual reels and including a plurality of wheel wedges displaying prize symbols and a prize selector, and a bonus wheel meter displayed above the virtual reels and including a number of bonus wheel symbols;

animating the virtual reels to simulate spinning and stopping the virtual reels to display an instance of a game including a bonus wheel symbol and a bonus wheel upgrade symbol appearing in the virtual reels with the virtual reels stopped;

animating a copy of the bonus wheel symbol to move from the virtual reels to appear on the bonus wheel meter to increase the number of bonus wheel symbols displayed in the bonus wheel meter;

accessing a bonus wheel data file including computer-executable instructions associated with each wheel wedge including a wheel wedge ID and an associated selection weight;

randomly selecting a wheel wedge displayed on the bonus wheel based on the associated selection weights using the random number generator;

modifying the bonus wheel by transforming a corresponding prize symbol displayed with the randomly selected wheel wedge to display an upgraded prize symbol;

26

animating a copy of the bonus wheel upgrade symbol to move from the virtual reels to appear on the bonus wheel meter; and

animating the bonus wheel to spin and stop upon determining the increased number of bonus wheel symbols included in the bonus wheel meter is equal to a pre-defined number of bonus wheel symbols.

10. The method of claim 9, including the processor performing the algorithm including the steps of:

randomly selecting the upgraded prize symbol from the bonus wheel data file that includes instructions associated with generating prize symbols being displayed on the bonus wheel.

11. The method of claim 9, including the processor performing the algorithm including the steps of:

displaying the bonus wheel with a wheel wedge displaying another bonus wheel symbol; and

initiating the spin of the bonus wheel and increasing the number of bonus wheel symbols included in the bonus wheel meter upon detecting an appearance of the another bonus wheel symbol adjacent the prize selector with the bonus wheel stopped.

12. The method of claim 9, including the processor performing the algorithm including the steps of:

displaying an extra wheel spin meter on the game screen indicating a number of extra wheel spins; and

initiating the bonus wheel feature by:

initiating an initial spin of the bonus wheel to display an initial prize symbol adjacent the prize selector; and

initiating a number of additional spins of the bonus wheel based on a number of extra wheel spins indicated by the extra wheel spin meter, each additional spin of the bonus wheel displaying an additional prize symbol adjacent the prize selector.

13. The method of claim 12, including the processor performing the algorithm including the steps of:

detecting an appearance of an extra wheel spin symbol appearing in the virtual reels with the virtual reels stopped and increasing the number of extra wheel spins indicated by the extra wheel spin meter based on the detected extra wheel spin symbol; and

increasing the number of bonus wheel symbols included in the bonus wheel meter based on the detected extra wheel spin symbol.

14. The method of claim 12, including the processor performing the algorithm including the steps of:

animating copies of the extra wheel spin symbol to the bonus wheel meter and to the extra wheel spin meter.

15. The method of claim 9, including the processor performing the algorithm including the steps of:

resetting the bonus wheel meter to include an initial number of bonus wheel symbols upon initiating the bonus wheel feature.

16. The method of claim 9, including the processor performing the algorithm including the steps of:

animating a copy of the bonus wheel symbol appearing in the virtual reels to the bonus wheel meter to increase the number of bonus wheel symbols included in the bonus wheel meter.

17. A non-transitory computer-readable storage media having computer-executable instructions embodied thereon to operate a gaming machine including a display device mounted to a cabinet and including a graphical user interface (GUI) display screen displaying computer-generated images thereon, and a control unit including a random number generator, a memory device storing computer-executable instructions, and a processor operably coupled to the display

27

device, when executed by the processor the computer-executable instructions cause the processor to perform an algorithm to display an animated sequence of computer-generated images on the display device including the steps of:

generating a plurality of virtual reels by:
 accessing a reel strip data file stored in the memory device including computer-executable instructions associated with each virtual reel including a plurality of reel strips including a plurality of fixed symbol positions and at least one reel strip including a variable symbol position;
 5 accessing a variable symbol reel strip data file stored in the memory device including computer-executable instructions associated with the variable symbol position including a plurality of special wheel symbols and associated selection weights;
 10 randomly selecting a special wheel symbol from the plurality of special wheel symbols using the random number generator;
 15 populating each fixed symbol position with a corresponding game symbol; and
 populating the variable symbol position with the randomly selected special wheel symbol;
 20 displaying a game screen on the display device GUI including the plurality of virtual reels displaying a plurality of game symbols, a bonus wheel positioned above the plurality of virtual reels and including a plurality of wheel wedges displaying prize symbols and a prize selector, and a bonus wheel meter displayed above the virtual reels and including a number of bonus wheel symbols;
 25 animating the virtual reels to simulate spinning and stopping the virtual reels to display an instance of a game including a bonus wheel symbol and a bonus wheel upgrade symbol appearing in the virtual reels with the virtual reels stopped;
 30 animating a copy of the bonus wheel symbol to move from the virtual reels to appear on the bonus wheel meter to increase the number of bonus wheel symbols displayed in the bonus wheel meter;
 35 accessing a bonus wheel data file including computer-executable instructions associated with each wheel wedge including a wheel wedge ID and an associated selection weight;

28

randomly selecting a wheel wedge displayed on the bonus wheel based on the associated selection weights using the random number generator;

modifying the bonus wheel by transforming a corresponding prize symbol displayed with the randomly selected wheel wedge to display an upgraded prize symbol; animating a copy of the bonus wheel upgrade symbol to move from the virtual reels to appear on the bonus wheel meter; and

animating the bonus wheel to spin and stop upon determining the increased number of bonus wheel symbols included in the bonus wheel meter is equal to a pre-defined number of bonus wheel symbols.

18. The non-transitory computer-readable storage media of claim 17, wherein the computer-executable instructions cause the processor to perform the algorithm including the steps of:

randomly selecting the upgraded prize symbol from the bonus wheel data file that includes instructions associated with generating prize symbols being displayed on the bonus wheel.

19. The non-transitory computer-readable storage media of claim 17, wherein the computer-executable instructions cause the processor to perform the algorithm including the steps of:

displaying the bonus wheel with a wheel wedge displaying another bonus wheel symbol; and
 initiating the spin of the bonus wheel and increasing the number of bonus wheel symbols included in the bonus wheel meter upon detecting an appearance of the another bonus wheel symbol adjacent the prize selector with the bonus wheel stopped.

20. The non-transitory computer-readable storage media of claim 17, wherein the computer-executable instructions cause the processor to perform the algorithm including the steps of:

displaying an extra wheel spin meter on the game screen indicating a number of extra wheel spins;
 detecting an appearance of an extra wheel spin symbol appearing in the virtual reels with the virtual reels stopped and increasing the number of extra wheel spins indicated by the extra wheel spin meter based on the detected extra wheel spin symbol; and
 increasing the number of bonus wheel symbols included in the bonus wheel meter based on the detected extra wheel spin symbol.
